US00D613533S

(12) **United States Design Patent**
Halvorson, Jr. et al.

(10) **Patent No.:** **US D613,533 S**
(45) **Date of Patent:** **** Apr. 13, 2010**

(54) **DENTAL CHAIR**

(75) Inventors: **Harold Halvorson, Jr.**, Beaverton, OR (US); **Stephen N. Weiler**, Dundee, OR (US)

(73) Assignee: **A-dec, Inc.**, Newberg, OR (US)

(**) Term: **14 Years**

(21) Appl. No.: **29/331,836**

(22) Filed: **Feb. 2, 2009**

(51) **LOC (9) Cl.** **06-01**

(52) **U.S. Cl.** **D6/500**

(58) **Field of Classification Search** D6/334-336, D6/360-361, 365, 367, 371, 373, 379, 500-502; D24/178, 183; 297/316, 313, 330, 391, 396, 297/344.17, 344.18, 423.1, 423.19, 68, 271.1, 297/353, 354.1; 601/49

See application file for complete search history.

(57) **CLAIM**

The ornamental design for a dental chair, as shown and described.

DESCRIPTION

FIG. 1 is a right side perspective view of a dental chair showing my new design;

FIG. 2 is a right side view, the left side view being a mirror image thereof;

FIG. 3 is a front view thereof; and,

FIG. 4 is a rear view thereof.

The broken lines shown herein are for illustrative purposes only and form no part of the claimed design. The bottom forms no part of the claimed design.

1 Claim, 3 Drawing Sheets
